UNITED STATES PATENT OFFICE.

HULDAH E. PRATT, OF DETROIT, MICHIGAN.

HAIR-WAVER.

1,399,874.

Specification of Letters Patent. Patented Dec. 13, 1921.

Application filed February 2, 1916, Serial No. 75,743. Renewed May 28, 1921. Serial No. 473,317.

To all whom it may concern:

Be it known that I, HULDAH E. PRATT, a citizen of the United States, residing at Detroit, in the county of Wayne and State of Michigan, have invented certain new and useful Improvements in Hair-Wavers, of which the following is a specification.

My invention relates to hair wavers and has for its object to provide a hair waver 10 constructed entirely of heavy wire which may be applied to the hair after the same has been dressed to cause the hair to be in ridges and valleys which in themselves are waved, thus presenting a double waved effect giving 15 an even, uniform and beautiful coiffure.

With the ordinary crimping tongs and wavers in present use the hair is first crimped or curled and afterwards combed and dressed. This usually necessitates the 20 help of a hair dresser, as it is very difficult to arrange the strands uniformly and to cause the waves to fall regularly. I provide my hair waver with tines which are curved to conform to the contour of the head, which 25 waver may hence be successively applied by oneself to various portions of the hair after the same has been dressed to give it the desired effect. I further position the tines in spaced relation to each other so that the 30 strands of hair are not broken between them or caused to become scorched by undue pressure against the warm tines. The sets of tines when the waver is closed are further positioned in spaced and parallel relation to 35 each other. The depth of the waves is hence dependent upon the space between the sets of tines and not upon the size of the tines, so that by holding the waver more or less open the depth of the waves may be varied.

40 The full objects and advantages of my invention will appear in connection with the detailed description thereof and are particularly pointed out in the claim.

In the drawings, illustrating the application of my invention in one form,—

45 Figure 1 is a view showing the application of my invention. Fig. 2 is a top view of my improved hair waver. Fig. 3 is a side view of the same when in closed position. Fig. 4 is a view similar to Fig. 3 of the hair waver in open position.

50 My improved form of hair waver, as best shown in Figs. 2, 3 and 4, comprises two members 10 and 11 hinged together. These 55 members are formed of continuous strips of wire which are looped at one end and joined

in the center, extending beyond the same at the other end and forming sets of tines. The member 10 is looped at 12 and the upper strand 13 of this wire is brought down at 14 60 and thereafter bent parallel to the remainder of the member. At 15 both wires are flattened, the ends thereof being undulated at 16 and 17 to form the tines of this member of the waver. Member 11 is formed similarly 65 to member 10, being looped at 18 and having a bent portion 19 which is thereafter brought down parallel to the remainder of the member. The two ends of this member are flattened at 20 somewhat closer to the loop handle 70 18 than the portions 15 of member 10, the extreme ends 21 and 22 of this member being also undulated to form two of the tines thereof. An additional tine 23, undulated to correspond to the heretofore-mentioned tines, 75 is flattened at one end and riveted to the flattened portions 20 of member 11 by rivets 24 and 25 passing through all three of said flattened portions. This tine is positioned between the tines 21 and 22 of member 11 and 80 is humped up at 26 in a position adjacent to the attachment with said member. The flattened portions 15 of member 10 are spaced to receive the hump 26 of tine 23 and are pivoted thereto by a rivet 27. The extreme end 85 28 of tine 23, as best shown in Fig. 3, protrudes beyond member 11 to form a stop against which member 10 may act when the waver is in its extreme closed position. It can be seen from Fig. 2 that the undulations 90 or waves in the tines come so that the spaces between the same are substantially equal.

In using the device the same is heated in the customary manner. In applying the same to the hair it is opened, as shown in 95 Fig. 4, the tines 16 and 17 of which having pointed ends 29 and 30 are inserted into the hair in the positions desired. Upon closing the device, as shown in Fig. 1, the hair is waved in two directions, one in the plane of 100 the hair and another one at right angles thereto. In order to have the waver readily adapt itself to the contour of the head after the hair has been dressed, the two sets of tines comprising members 10 and 11 are 105 curved in the arc of a circle as clearly shown in Fig. 3. It will hence be comprehended that the waver may easily be used by oneself to wave the hair at the rear of the head as well as at the front, and that the waver may 110 be successively placed on different portions of the hair to uniformly and evenly wave

any desired portions of the same. As the hair is caused to roll over and under the various tines of the waver the distance between the sets of tines, or the members 10 and 11, 5 will vary the depth of the wave. By holding the handles 12 and 18 a short distance apart the sets of tines may be brought closer together and the waves made less pronounced. This has the effect of producing different effects in the appearance of the coiffure.

The advantages of my invention are manifest. When the device is closed the members are in spaced relation to each other, so that the hair can in no way become cracked or 15 broken. This is especially true at the hinge, where, as it can be seen from Fig. 4, the hair cannot get tangled or caught. When the hair reaches the vertex of the tines as formed in that figure the same is remote from the 20 hinge, and as the device is closed the portion 26 of the hinge is brought into effect and serves to prevent the hair from further entering the joint after the device has been

closed. The device can be made quite inexpensively and hence its use and application 25 may be made unlimited.

I claim:

A hair waver comprising two handles, two sets of tines attached respectively to said handles, the tines of the respective sets in 30 alternation being spaced transversely from each other, all of the tines having transverse undulations and being curved to conform substantially to the contour of the head of a person, and means for pivoting said handles to each other in such manner that the tines of one set will pass from a position above the other set to a position below the same when said handles are operated from open to closed position.

In testimony whereof I affix my signature in presence of two witnesses.

HULDAH E. PRATT.
